THREAD GAUGE

Maynard E. Kraushaar, Pasadena, Calif.

Application May 18, 1953, Serial No. 355,783

2 Claims. (Cl. 33—199)

This invention relates to a thread gauge, and more particularly to a gauge for use by a machinist while engaged in the process of forming a screw thread.

Conventional thread gauges, for example of the ring or thread wire type, are subject to a number of disadvantages in that they are difficult to use and do not indicate to the machinist what must be done to correct an inaccuracy in the thread being formed. In addition, conventional gauges do not show up variations in the angles of the thread faces relative to the axis of the screw, or variations in the dimensions of various portions of the thread. A ring gauge, for example, merely indicates to the machinist that a previously formed thread is substantially correct, and does not enable the machinist to determine the exact manner in which an improperly formed thread may be corrected. A thread wire gauge is subject to the same defects since it also does not indicate how much must be taken off on the next cutting or grinding operation in order to reduce the thread to the desired size. Furthermore, ring and thread wire gauges may not conveniently be used at various points along a screw thread to indicate when one portion of the screw is at variance with another, and do not indicate when one or more faces of the thread are not at an exact sixty-degree angle with the axis of the screw.

In view of the above problems characterizing the field of thread gauges, it is an object of the present invention to provide a simple, inexpensive, and reliable thread gauge which may be easily employed to check various portions of a screw thread, and when so employed will indicate to the operator how much metal to take off on the next cutting or grinding operation to provide a thread having the desired dimensions.

Another object of the invention is to provide a thread gauge adapted to indicate the precise pitch diameter of a standard screw thread, and also when any of the faces of a standard screw thread is not at a precise sixty-degree angle with the longitudinal axis of the screw being formed.

An additional object is to provide a handle which may be readily manipulated to position the gauge at various points on the thread, yet which will not interfere with the precise operation of the body of the gauge.

These and other objects and advantages of the invention will be more fully set forth in the following specification and claims considered in connection with the attached drawing to which they relate.

In the drawing:

Figure 1 is a greatly enlarged longitudinal elevational view illustrating the thread gauge in mounted position on a lead screw;

Figure 2 is a perspective view showing a micrometer as employed in reading the resultant distance across the screw and gauge; and

Figure 3 is a central sectional view, longitudinally of the gauge, illustrating the construction and mounting of the handle elements.

Referring to the drawing, the gauge, indicated gen-

2

erally by the reference character 10, is illustrated as employed in forming a precision lead screw 11 of the standard type. The screw thread being standard in the present illustration, it will have straight or flat sides 12 and 13 which form a sixty-degree angle with each other as well as with the longitudinal axis of the screw. Although the lead screw 11 is illustrated as having a flat 14 at its root and a corresponding flat 15 at its ridge, the gauge of the present invention will work equally well where the thread sides 12 and 13 come to a sharp corner at either or both the root and the ridge.

The gauge 10 comprises a triangular body block 17, and a handle structure which is formed with a rigid portion 18 and a flexible portion 19. As will be described in detail subsequently, the handle structure is constructed so that the machinist may manipulate the gauge with ease and without interfering with the accuracy of the gauging operation.

Block 17 is precision formed of hardened tool steel, and is an equilateral triangle in transverse section so that a sixty-degree angle is formed between intersecting faces. Any two faces of block 17 will therefore rest, as shown in Figure 1, in exact abutment with the opposed thread sides 12 and 13 when the block is mounted transversely of the screw axis as indicated.

It is essential, for accurate use of the gauge, that a maximum bearing surface or area result when the gauge is positioned on the lead screw. Accordingly, the three corners or edges 21—23 of the block are formed with flats of different widths so that the inner corner of the block may be selected for positioning as close as possible to the thread root 14 without actually engaging it. One such flat, at the corner 21, is approximately .002 inch in width, while the flats at the corners 22 and 23 are .008 and .015 inch in width, respectively. It is to be understood that the showing in the drawing is greatly exaggerated both as to the widths of the flats and as to the actual size of the block 17. In a preferred construction, the length of the block 17, transversely of the lead screw 11, is approximately half an inch.

In using the body portion 17 of thread gauge 10, the machinist selects a piece of cylindrical stock of given major diameter, indicated at D in Figure 1, and uses a lathe or thread grinder to rough form the thread. Such rough forming is effected by standard methods and with knowledge of the root diameter R, the pitch diameter E, and the pitch. After the lead screw is thus rough formed, gauge block 17 is positioned with two of its faces in abutment, respectively, with the thread sides 12 and 13. The inner edge 21, 22, or 23 is selected as the one which will be closest to the root 14 as previously mentioned. A micrometer, indicated in Figure 2 at 26, is then employed to take the reading M across both block 17 and the screw 11.

It can be shown that the micrometer reading M, in inches, equals

$$D + G - \frac{.75775}{N}$$

for the national standard screw thread, where D is the major diameter, in inches, G is the length, in inches, of an altitude of the equilateral triangle making up the block 17, and N is the pitch in threads per inch. The correct reading of M for any thread may therefore be determined since D and N are known in any shop problem, and G is known for any gauge. The following is an extract from a table which may be utilized in the shop to save the machinist from calculating what the reading of M

should be for various standard threads and standard major diameters:

Screw Size	Basic Major Diameter	Measure Over Gauge (M)
0-80	.060	.42553
1-72	.073	.43748
1-64	.086	.44917
3-56	.099	.46047
3-48	.099	.45822
4-48	.112	.47122
4-40	.112	.46806
5-44	.125	.48278
5-40	.125	.48106
6-40	.138	.49406

After the rough forming operation, the actual reading of M is compared to the value given either by the above table or by calculation, and finish cuts are taken until the reading of M on micrometer 26 is the same as the table reading, it then being known that the thread is perfectly formed and has the desired pitch diameter.

To illustrate the above, a representative problem will be described. Let it be assumed that it is desired to form an 0-80 national standard thread on stock having a basic major diameter of .060 inch. Referring to the above table, the machinist will note that the reading of M for such a thread will be .42553 inch. By standard shop processes the machinist will form a rough thread which is somewhat larger than the finished product. He will then position the block as described above, and take a reading with micrometer 26. Such a reading would, for example, be .42560 inch, which is a little less than .0001 greater than the correct reading. Using this information, the machinist will be able to set his tools with exact knowledge of how much to take off on the next or finish cut. Another reading is taken after the finish cut is made, and it is known that the thread is perfectly formed if the micrometer reading and the value of M on the table coincide. The process is, of course, repeated if the micrometer reading is again slightly larger than the table value of M.

It is a feature of the invention that the reading of M is not merely taken at one location, but instead is taken at a number of points along the full length of screw 11. In this way it is determined whether the various sections of the screw are exactly equal to each other, as well as whether the sections each have the correct value of M for the thread which it is desired to form. When the readings of M are thus taken at one or more points along the screw, it may be readily determined whether or not the faces 12 and 13 form exact sixty-degree angles with each other as well as with the longitudinal screw axis. This is to be distinguished from conventional gauges, which may be utilized to determine whether the thread sides form a sixty-degree angle with each other, but which do not indicate when one or the other of the thread sides is tilted with respect to the screw axis. Thus, for example, the side 12 may form a sixty-degree angle with side 13, yet it may form an acute angle of sixty-two degrees with the longitudinal axis of the screw if the side 13 forms an acute angle of fifty-eight degrees. Such undesired tilting of the thread sides is readily determined, according to the present invention, by merely sighting between the micrometer end face 27 and the abutting surface of gauge block 17. If any light appears between these components, the machinist will know that the block 17, and consequently the thread sides 12 and 13, are tilted with respect to the screw axis.

In view of the above, it may be seen that the precise positioning of block 17 is of extreme importance since the gauge will not read properly if the block faces are not in continuous engagement with the thread sides 12 and 13. Where the abutment between the faces of block 17 and the thread sides is not perfect, the reading will be

incorrect and the step of sighting between the micrometer end 27 and the cooperating block face will not give a true indication of whether the thread sides are tilted with respect to the screw axis.

According to the present invention, the precise mounting of block 17 is accomplished when the slight micrometer pressure is applied, even though the initial block mounting may be improper and even though the fingers of the machinist are not steady. Such desired action results from use of the handle component of the gauge, which consists of a rigid portion 18 and flexible portion 19 as previously indicated. The rigid portion 18 takes the shape of a bail, of circular section, having side portions 29 extending parallel to each other and in planes perpendicular to the longitudinal axis of gauge block 17. The sides 29 are connected, remote from block 17, by an integral end section, indicated at 31, extending parallel to the block axis. The portions of bail sides 29 adjacent block 17 are bent inwardly at right angles for loose insertion into an axial passage 32 bored in the block. The clearance 33 between each bail end and the block 17 is sufficient to permit substantial movement of the rigid portion 18 of the handle without any interference with the precise mounting of gauge block 17.

The flexible component 19 of the gauge handle structure takes the form of a strip of very thin aluminum, one end 34 of which is bent around the bail portion 31 and secured, as by gluing, to the main body of the strip. The flexible component 19 may, if desired, be inscribed with the above stated equation so that it will be readily available to the machinist as he uses the gauge.

In the operation of the handle structure as employed in connection with the block component of the gauge, the machinist grasps the rigid portion 18 of the handle and carries the block 17 until it is in approximate position. The micrometer 26 is then placed around the screw and block and the flexible component 19 of the handle is grasped, for example between two fingers of the machinist, to maintain the rigid component 18 out of engagement with lead screw 11 or other interfering structures. While the component 19 is thus held, the micrometer 26 is turned to obtain the reading.

When the gauge 10 is employed in this manner, the block 17 is nested between the thread sides 12 and 13 by pressure due almost entirely to its weight and to the slight force exerted by the micrometer 26. The rigid or bail portion 18 of the handle in no way affects the final positioning of the block 17 since this portion is not grasped by the machinist during the final portions of the operation, and further because the clearances 33 are adequate to permit slight shifting of the bail 18 without any effect on the block. The flexible component 19 of the handle, although grasped during the final reading operation, does not affect the final positioning of block 17 since any vibration or unsteadiness of the machinist's fingers will be damped before reaching the bail. If not completely eliminated, such a vibration will have no effect on the block 17 because of the clearance 33 between the bail and block. The invention thus provides for the ready manipulation and positioning of the gauge block 17 by a handle which is specially designed to prevent any interference with the accuracy of the reading.

The described operation of the handle components in facilitating the positioning of block 17 in the absence of interference with the accuracy of a reading, is further enhanced since the handle components 18 and 19 are extremely light and will not have substantial effect in tilting the block 17 even though the flexible strip 19 is accidentally released during the taking of a reading. Since the block 17 will not be tilted, the accuracy of the reading of M, as well as the accuracy of a sight between micrometer end 27 and the cooperating face of the gauge, will be left substantially unimpaired.

While the particular apparatus herein shown and described in detail is fully capable of attaining the objects

and providing the advantages hereinbefore stated, it is to be understood that it is merely illustrative of the presently preferred embodiments of the invention and that no limitations are intended to the details of construction or design herein shown other than as defined in the appended claims.

I claim:

1. A thread gauge, comprising a small metal block any transverse section of which is an equilateral triangle, said block having an axial bore formed therethrough and of substantial diameter, a light-weight rigid metal bail having parallel sides extending transverse to the axis of said block and connected at their ends remote from said block by an integral end portion formed parallel to said axis, the ends of said bail sides adjacent said block being inwardly bent at right angles to said sides and extending loosely into opposite ends of said bore, and a thin strip of highly flexible material mounted on said end portion of said bail,

5

said thin strip being adapted to be held by an operator during the final portions of a gauging operation.

2. The invention as claimed in claim 1, wherein said flexible material is aluminum, and substantial clearance is provided between said ends of said bail sides and the wall of said bore, whereby vibration of said strip during a gauging operation is ineffective to alter the position of said block.
